CLAIM

The ornamental design for kiosk, as shown and described.

DESCRIPTION

FIG. 1 is a perspective view of a kiosk showing our new design.

FIG. 2 is a front elevation view of the kiosk of FIG. 1.

FIG. 3 is a back elevation view of the kiosk of FIG. 1.

FIG. 4 is a first side elevation view of the kiosk of FIG. 1. FIG. 5 is a second side elevation view of the kiosk of FIG. 1.

FIG. 6 is a top plan view of the kiosk of FIG. 1; and,

FIG. 7 is a bottom plan view of the kiosk of FIG. 1.

The portions of the drawings shown in broken lines represent environmental structure and form no part of the claimed design.

1 Claim, 4 Drawing Sheets

See application file for complete search history.
